[57] CLAIM

The design for a gravity feed display, shown and described.

DESCRIPTION

FIG. 1 is a perspective view of a wall mounted gravity feed dispenser showing our new design;

FIG. 2 is a front elevational view thereof;

FIG. 3 is a left side elevational view thereof, the right side elevational view being a mirror image duplicate thereof;

FIG. 4 is a rear elevational view thereof;

FIG. 5 is a top plan view thereof; and,

FIG. 6 is a bottom plan view thereof.
